UNITED STATES PATENT OFFICE

2,326,015

TEXTILE IRONING PRESS

Ernest Davis, Syracuse, N. Y., assignor to The Prosperity Company, Inc., Syracuse, N. Y., a corporation of New York

Application March 24, 1939, Serial No. 263,961

12 Claims. (Cl. 33—40)

This invention relates to pressing machines, and more particularly to a new and useful textile ironing press and the like for use in the press-finishing of apparel, clothing, suits, and fabrics. The press is more especially used in laundries for ironing laundered goods and washed apparel, and also fills a need in clothing factories where heavy pressure is required in edge and seam pressing.

This application is a continuation in part of my earlier application for patent Serial Number 104,672, filed October 6, 1936.

This invention is illustrated by showing a new and improved scissors-type textile-ironing and pressing machine, so called because of the up and down arcuate movement of its upper ironing head pivoted on an axis located in the rear of and proximate the pressure plane of the coacting pressing elements or jaws of well known form, generally called the head and buck. While one or more preferred examples of movable upper head and stationary lower padded buck types of pressing machines are illustrated herein, the invention may be used in connection with other types of jaw-motion presses.

The invention has for its general object a pressing machine actuating mechanism including a uniformly constant output motor and motion transmitting means operated thereby by which the static inertia of the press head, when open, is easily overcome and the head set in motion without jar or shock, and quickly moved, through the greater part of its closing movement, to nearly closed position through a long, quick acting, high ratio leverage, and into final closed position through a low ratio leverage, in one continuous uniform operation of the prime mover or during the transfer from the closing and opening movements and during the transfer from the high ratio to the low ratio during closing, and all without shocks, jars, or slamming.

More specifically, it has for its object a pressing machine in which the head closes in a downward and forward arcuate path with the final closing movement in a short upright portion of the arc of movement practically at a right angle to the pressing plane or face of the lower pressing element or buck, and the upright actuating lever having successive forward lever movement and vertical pull link movement under the uniformly constant force of the motor, and first fulcrums about an axis located near the lower end of the lever so that the motion thereof is transferred to the press head through the long arm of the lever and then as the press closes, the lever moves about an axis at its upper end

and brings into action the low ratio leverage which forces, or pulls, the actuating lever downwardly substantially vertically as a pull link, clamping the press head practically rectilinearly through the upright portion of its arcuate path into final heavy pressure position to always deliver maximum pressure and compensate or follow up for such variables as different thicknesses of the pieces of work, different thicknesses of and compression of the pad on the buck, and settling or permanently setting of the pad.

It further has for its object, actuating mechanism or motion transmitting mechanism between the motor and the head for holding the fulcrum of the lever from substantial swinging movement while the press head is passing through the downward and forward portion of its arc of movement, and means actuated by the lever during its swinging movement about an axis at its upper end for moving the lever downward as a pull link only when the head is passing through the upright portion of its arc of movement.

It further has for its object, actuating mechanism or motion transmitting mechanism between the motor and the head including a toggle which effects the final closing through the low leverage ratio, and means for holding the toggle folded or cocked during the preliminary closing of the press to a point before final pressure is applied, and to cause the toggle to straighten during the final swinging movement of the lever by the motor and thus apply heavy pressure through the straightening toggle while the lever acts as a pull link.

It further has for its object an arrangement of the actuating mechanism whereby the head carrying lever and the actuating lever therefor are nested and streamlined, or whereby one is received within the other when the press is open or closed, particularly the upper portions thereof above the table of the press and in the rear of the buck, and also whereby the actuating lever and the head carrying lever do not move rearwardly during the opening and closing movement to the rear of a vertical plane tangent to the rear-most surface of the upper portion of the lever, this feature being in the interest of economy in floor space, safety to persons that may be near the machine when in operation, and in the interest of appearance.

Other objects appear throughout the specification.

In my invention, the variable-stroke leverage, operatively interconnected between a motor means of uniformly constant-power output and

an ironing head resisted by constantly varying forces, reconciles the conflict, that is, the lack of common operating characteristics between the motor and the head, and delivers from the motor to the head a smooth flow of power which compensates for such conflicting problem factors as starting the head from standstill, the increasing resistance of the counter-balancing springs as they stretch, the necessity of conserving the motor stroke until the end, the requirement not to impact and hammer the buck pad, overcoming the rapid build-up of spring-pad resistance once final jaw compression begins, and accomplishing these ends without carrying all the load or thrust upon cam and roller bearing surfaces which is one convenient method employed here in the control of the motion of the variable-stroke leverage of this invention. By test, it is now found that with a motor means of given size, about five times more jaw compression can be exerted on the work and pad with this new textile press than with presses of conventional form.

The drawings

With the foregoing and other objects in view, the accompanying drawings illustrate several principal examples of the invention, particularly three main forms of leverages, wherein certain modifications in form, proportion, and mode of operation may be made without departing from the principles and advantages taught in this disclosure, and wherein—

Figures 1 through 7 show a first form of the invention in two of its simpler constructions. A low-power compound-motion leverage mechanism first closes the movable head to initial position, i. e., light contact with the padding on the buck, whereupon a high-power heavy-pressure leverage mechanism, having greater efficiency than the conventional toggle leverage, imparts final-heavy jaw compression to the work on the buck; and the motion is continuous from beginning to end, thereby avoiding the two-step action so characteristic of conventional presses, especially of two cylinder presses.

Figure 1 is a side elevation of the press in wide-open position, with the pedestal frame in section to expose the press-operating mechanism, i. e., its leverage concealed therein.

Sheet 2 including Figures 2, 3, 4 and 5 is a motion study showing successive positions of the press from beginning to end of its closing motion effected in one continuous stroke without a pause.

Figure 2 shows the press in wide-open position; Figure 3 in mid-closed position; and Figure 4 shows it initially closed where the head is just touching but not squeezing the padded buck. When it is noted that the head has swung through its long arc and reached its initially-closed position in Figure 4, it will then be appreciated that the stroke of the motor is only partly expended. Thus there remains a long portion of its power stroke to move the head from Figure 4 to Figure 5 position. Figure 5 shows the press stalled under final ironing pressure, and by comparison with Figure 4 it will be observed that the padding on the lower buck is now under maximum compression.

Figure 6 is a side view of the press in one of its more nearly commercial forms, with certain parts omitted for clarity, and showing a new crank-actuated spring-counterbalancing means for opening the press; and Figure 7 is a rear projection thereof, more particularly made on the section line 7—7. These two views are a development

from the previous views, and for the sake of simplicity may be treated as a part of the first form of construction.

Figure 8 is a side view of the second form of construction, wherein the same low-power closing leverage is employed as before, but the high-power heavy-pressure leverage is featured by a stationary cam acting as a guide for a traveling fulcrum on which the low-power lever means is carried.

Figure 9 is a fragmentary upper rear view showing the assembly of the ironing head with its arm and a lever constituting a part of the compound leverage.

Figure 10 is a top or plan view of the head-carrying arm (also known as the yoke) looking down upon Figure 9. Note the long single-bearing pin through the tines of the bifurcated arm, and also note a set of short twin-bearing pins outside the arm tines in axial alignment with the bearing holes into which they are adapted to fit.

Figures 9 and 10 are to be read with other views in the drawings, since all forms of the invention shown herein employ this same lever-and-arm assembly with the ironing head. This assembly provides a shielding means for closing the operating clearance between the arm and lever; it insures safety because a careless person if behind the press cannot get his hands in the mechanism, and it enhances the appearance of the straight simple lines of the press.

Figure 11 is a diagram of the pneumatic hook-up comprising an air motor with a two-hand control to illustrate a feature of the press. The parts are shown in open-press position. Since any suitable pneumatic control may be used with my invention, no claim is made herein to this particular motor means and control.

Figures 12 through 16 show the invention as further developed into a third form. Its full-automatic compound leverage comprises fewer parts, and the action thereof is characterized by a mode of operation which produces somewhat greater jaw compression and speed for a given size air motor than the other two forms. A movable cam, guiding a traveling fulcrum, together with a hydraulic speed governor, in combination, make for more efficient use of the power available from a given size motor means. This third form, in its new combination, permits the press to be operated at higher speed than the previous forms; consequently press operators can attain greater ironing production.

Figure 12 shows the third form of press wide open, and Figure 13 shows it fully closed. The hydraulic speed governor, by which it is now possible to increase the velocity of the ironing head, is not seen in these two views because it is mounted on the far side.

Figure 14 is a front view of the third form of the invention. The press is closed, and the front of the frame is broken away to expose the leverage parts. Note the hydraulic governor on the right side of the press, and it is slightly enlarged for clarity. The governor is directly connected by a coupling with a shaft of the leverage and is driven by the latter, and a link of the toggle is fixed to that shaft. This hydraulic governor comprises a two-cylinder double-acting shock absorber and speed controller. By its use here, in a new way, it is now feasible to close the ironing head at high velocity because the governor holds the leverage to its pre-adjusted speed and prevents the motor means from exceeding that speed. Also, the opening of the head can be ac-

complished at high speed, in fact at its maximum attainable velocity, and the shock absorber checks the momentum at the end of the press-opening motion and does not retard the quick opening of the press.

Figure 15 is a detached view of the hydraulic governor, looking at that end of the governor shaft which connects directly with the press leverage, and the governor parts are shown in open-press position.

Figure 16 is a top view of the speed governor, as taken on the line 16-16 of Figures 14 and 15, that is, the cover is removed, thus looking down into the device.

The press construction in general

Reference is now made to the drawings for a more detailed description of the illustrated examples of the invention, but a description is first made of the press in general, i. e., the type of press chosen for illustrating the leverage and other features of the invention in its several forms. A frame preferably is made of steel plate stock fabricated and welded together to form a rigid pedestal enclosing the operating parts. Thus the frame may consist of side spaced plates 2 with a front plate 3 which leaves the rear of the frame open, as shown. The upright frame plates 2 and 3 may preferably rise from a marginal flanged base 4. The rear upper part of the frame is provided with a pair of parallel upstanding spaced horns or brackets 5 to receive the operating means for the movable-pressing head.

The frame 2, 3 is surmounted with a top plate 6 which may also form a table, or a support for a table, to conveniently hold the work during the ironing or pressing operation. Usually a thin sheet metal table (not shown) is placed upon the frame top 6, and such table may be as long or longer than the pressing jaws and consequently overhangs the frame sides 2. The frame top 6, or more particularly the table when placed thereon, may also extend forwardly beyond the front plate 3 and is turned down to provide a front marginal flange 7. Inasmuch as the table, to finish off and cover the frame top 6, preferably would be made of thin sheet metal, the front edge 7 provides rigidity and a convenient covering means for the control valves and their manuals at the front of the press. The frame top 6 (with its covering table not shown) may extend rearwardly under the pressing jaws and curves upwardly at 8 to form a back plate against which the edges of the apparel or work may rest and be protected during the pressing operation.

A bearing or frame bracket 9 is rigidly carried underneath the frame top 6 and depends therefrom near the center portion and at the rear of the frame 2, 3. It is used as a stationary-frame pivot for operatively mounting the new form of high-power heavy-pressure toggle leverage having a variable stroke or swing, as later described. Likewise, at the front of the press, there is shown an ear or bearing bracket 10 for mounting an adjustable-frame pivot for the new leverage. A little lower in the frame, a similar bearing bracket 11 affords a support for the motor means.

An upstanding post or pedestal bracket 12 is placed on top of the frame plate 6 to carry the lower pressing jaw or padded buck. This post 12 sometimes assumes a horizontal U-shape form, when viewed from the front of the press (see Figure 14), which explains why it is known in the trade as a "goose neck"; and this is especially true if the buck is long because it allows

the operator to more easily make her "lay" of the work. A conventional steam-heated buck 15 is supported on the upper end of the goose neck 12 and is provided with an overlay padding 16. The pad 16 usually consists of matted or nested short coil springs interposed vertically under layers of felted padding by which to provide a rather substantial and thick resilient bed on which to lay and dress the work.

10 The movable ironing head 17 has a long up and down motion to afford a wide-opening press for the convenience of the operator. A head-carrying arm 19, frequently called the yoke, has its front end suitably attached to the head 17. Usually a rocking or equalizing mounting means 15 is interconnected between the head arm or yoke 19 and the head 17 to enable the ironing surface of the head to equalize and adjust for variable thicknesses of work spread upon the padded buck, and this is partly shown in Figures 13 and 14, although this is not a feature claimed herein. The head-carrying arm 19 is preferably made out of steel and is hollow for lightness. It may be made in the form of a channel or an inverted U-shaped member with its open part on the lower side. Thus the top of the rather wide head-carrying arm 19 is smooth and its sides are closed, so that it presents a neat appearance.

15 The head-carrying arm 19 is bifurcated by a slot 20 extending upwardly from its rear end towards the head 17, and this slot provides an operating clearance to receive an actuating lever presently described. This slotted construction provides two spaced tines 21 constituting the major length of the head arm 19. This arm extends horizontally rearwardly and curves downwardly behind the pressing jaws 15 and 17 where it is pivotally mounted by two horizontal spaced bearing pins 22 carried by the two spaced upstanding frame brackets 5. Each bearing pin 22 stops flush with the inner face of its arm tine 21 so as not to extend into and obstruct the slot or clearance 20. The head-arm slot 20 is left entirely open and unobstructed for the up and down movement, across the bearing axis 22, of a lever means for swinging the ironing head 17 up and down. The spaced frame brackets 5 carry their twin bearings 22 which define the pressing plane, that is, the meeting plane of the head and buck, the axis 22 lying parallel to the longitudinal axis of the pressing jaws 15 and 17.

20 The foregoing construction affords an arcuate movement of the head 17 around its pivotal axis 22, the action being such that the head swings upwardly and rearwardly from the buck 15, thereby fully exposing the latter so the operator may lay and smooth the work thereupon preliminary to the pressing operation. As said before, this general form of jaw-motion press is sometimes called a scissors-pressing machine because of this characteristic movement of the head 17 about its rear axis 22. The rear end of the arm 19 carries a rubber padded stop bracket 23 reaching below the pivot 22. This stop 23 resiliently comes to rest against the press frame, say the back plate 6 thereof, and thus quietly stops and limits the upward travel of the head 17.

25 A specially designed head actuating member 25, in the form of a compound-motion lever, is mounted at the rear within the press frame and within the slot 20 of the head-carrying arm 19. The upper actuating end 26 of this lever is curved forwardly into the slotted arm 19 and pivotally connected thereto by a bearing pin 27. The upper lever end 26 is made on the same contour

as the head-carrying arm or yoke 19 so that when the press is closed there results a smooth neat appearing lever-and-arm assembly 19, 26 as shown in the closed views. In other words, the upper end 26 of the compound-motion lever 25 fully occupies and closes the slotted operating space 20 in the head arm 19 and is about the same depth as the tines 21 so that the member 26 swings within the member 19 without opening up an operating space in between these two relatively movable parts.

The joint action of the two swinging members 26 and 19 provides a wholly closed and shielded head-operating mechanism at the upper rear portion of the machine so that no danger exists in handling, or to persons who may be standing behind the machine while in operation, as during the operation, there are no moving parts projecting or kicking rearwardly during the opening and closing of the press. This part of the description is especially considered in connection with Figures 1, 8 and 9, inasmuch as it will be noted that these are side and rear views in several different positions. Thus is brought out the fact that maximum up and down travel of the two members 19 and 26 is accomplished without opening up a dangerous and unsightly operating-clearance space between them. In wide-open position (Figure 1), it is noted that the right-hand dotted edge of the lever end 26 remains concealed within its embracing head arm 19, 21. This over or innerlapping of side surfaces of the two relatively movable lever members 19 and 26 provides a shielding means and thus fills the operating clearance 20 on both sides of the arm and actuator assembly 19, 26. This arrangement improves the solid closed appearance and general safety of the machine.

In Figure 8 the upper end 26 of the actuating lever is purposely shown in dotted lines behind the front tine 21 for clarity in illustration, but in actual manufacture the upper surface of the head-carrying arm 19 and its lever 26 may be made perfectly smooth and flush with each other to present a neat appearing design, wherein the parts merge by conforming to like or similar contour lines. My invention, therefore, takes into account not only safety, utility and simplicity, but also favors good appearance in the structural design of the press.

The compound-motion lever 25 extends vertically downwardly for a considerable distance and its lower extremity 28 is near the bottom of the press. When the press is open, the lower end 28 is substantially under the axis 22 of the pressing head 17. When the press is closed (Figures 4, 5, 6, 8, 13 and 14), the lower lever end 28 is displaced outwardly from the pedestal frame 2, 3 to a position not further than occupied by the outer margin of the upper lever end 26 when the press is open (Figures 1, 2 and 12). This compact and vertically arranged operating assembly produces a pressing machine which may be installed close to the wall and occupies minimum floor space.

The lower end 28 and central portion 25 of the lever curves inwardly toward the front 3 of the press frame to provide a projecting bearing bracket or arm 29 offset from the longitudinal axis of the lever. This offset bearing arm 29 curves upwardly under and in front of the bearing bracket 9 when the press is open, providing for compactness in design and construction, and it is about one-third of the distance upwardly from the lower lever extremity 28. It will be

shown that the lever extension arm 29 is operatively connected with a variable-stroke high-power heavy-pressure leverage, while the lower end 28 is operatively connected with a prime mover such as motor means or other actuator.

The motor will be shown to not only actuate the lever 25 to first or initially close the press but also actuates the heavy-pressure leverage through said lever 25 without pause or interruption. The full movement from Figure 2 to Figure 5 position is therefore a smooth continuous one performed by the simple low-power closing leverage 19, 25 which alone is not capable of imparting heavy ironing pressure to the head 17, although its leverage ratio is well suited for initially swinging the head 17 down to the buck 16. As a matter of fact, the lower end 28 is seen to be only one-third the length of the upper end 26, taking the arm 29 as the fulcrum of the long lever 25.

The high-power heavy-pressure toggle leverage shown in Figures 1 thru 7

The compound-motion lever 25 is pivotally mounted or fulcrumed between its ends, about two-thirds down, for bodily shiftable swinging motion relatively to the press frame, upon a heavy-pressure leverage of improved toggle formation comprising comparatively short upper and lower links 31 and 32. These two short links are pivotally connected together by a bearing pin forming a toggle-knee joint 33. The upper link 31 is carried by or pivoted upon a stationary-frame bearing 34 in bracket 9, while the other link 32 has its lower end connected with the forwardly extending lever arm 29 by a free or compound-motion pivot 35 which follows the motion of the lever 25 in opening and closing the press.

The leverage ratio of the toggle 31, 32 is suited only to the production of heavy ironing pressure; hence it is referred to herein as a high-ratio or a high-power leverage for the lack of a better name. Its force multiplying amplitude is so great as to wholly unsuit it as a means for initially closing the press, a function not requiring high power in the first place. A multiplication of the motive force, into a mechanical advantage stepped up or amplified many times, is only required in going from Figure 4 to 5 position, and that amounts to a head movement of only an inch more or less, whereas the travel from Figures 2 to 4 may be twenty times greater.

In my experiments it is found that the principle of my invention can be carried into effect with types and forms of low ratio lever means other than that shown herein and indicated at 19, 25, and with high ratio lever means other than the characteristic toggle 31, 32 and its equivalent forms shown in Figures 8 and 12. At the same time, it is believed that the particular forms of the leverages, herein chosen to illustrate my invention and its principles, are also new and inventive.

The upper link 31 is integral with a counterbalancing arm 36 extending rearwardly from the frame bearing 34. A press-opening or counterbalancing spring 37 has its upper end mounted on a pin 38 carried on the counterbalancing arm 36, while the lower spring end is attached to the press frame at 39. It is often desirable in presses having large and heavy movable heads to employ more than one spring 37 in order to increase the head-lifting force required to open the press. That is shown in the advanced views (Figures 6 and 7), but a single spring 37 is first shown to

illustrate the invention (Figures 1 through 7) in its simplest form.

The lower link 32 of the heavy-pressure toggle linkage 31, 32 is made integral with a guide link or variable-stroke toggle-adjusting arm 41. This link 41 extends laterally forward toward the frame 3 from and as a part of the side of the short upright link 32. The front end of the link arm 41 turns downwardly from the top 6 of the press. In other words, this member has a wide end 32 with close centers 33 and 35 in an upright plane, and has its long narrow end 41 extending therefrom a distance greater than the length of the upright link 32. The end 32 of the arm 41 may be made in the form of a fork to embrace the two parts 29 and 31 pivotally connected therewith.

The free end of the projecting arm 41 is pivotally connected through a pivot 42 with one end of a short upright guide or a radius link 43. The latter in turn has its other end pivotally connected, through an adjustable-frame bearing 44, with the short arm of a toggle-adjusting lever, say a bell crank 45. Hence the radius link must swing on its pivot 44. The bell crank 45 is mounted inside the machine on a stationary-frame bearing 47, with its other end extending alongside the front frame 3, say upwardly. A hand-wheel 48 is journaled in the frame 3 and is fixed on a screw which is operatively threaded into the longer part of the toggle-adjusting lever 45. By turning the handwheel 48 one way or the other, its screw runs in and out of a conventional swivel nut mounted in one arm of the bell crank 45 which moves the latter about its frame pivot 47.

The foregoing provides for close or fine up and down movement of the adjustable-frame bearing 44 to adjust the arm 41 around the compound-motion pivot 35 of the lever 25. Hence the heavy-pressure toggle 31, 32 is adjustable in relation to the press frame and hence the buck 15. The purpose thereof is to alter the relative angular positions of the three toggle bearings or axes 33, 34, and 35, in relation to the upper pivot 27 of the swingable pull lever 25, by which to set the high-power leverage 31, 32 to apply more or less pressure between the coacting press jaws. While this adjustment is infrequently used, it is or may be provided for the purpose of setting or resetting the heavy-pressure leverage 31, 32 so as to compensate for the variable factors which may arise when the padding 16 is changed, or more particularly when a pad of one thickness is replaced by one of different thickness.

An actuating means comprising a fluid-pressure or pneumatic-motor means 50 is operatively connected with the lower end 28 of the lever 25 to apply an angular force outwardly thereon and fulcrum the lever on its compound-motion pivot 35 carried by the high-power leverage. The cylinder 50 has one end mounted on a stationary-frame pivot 51 which permits its other end to oscillate and follow the motion of the lower end of the lever 25. A piston 52 with its connecting rod 53 is pivotally attached by a wrist pin 54 with the lever end 28. An air hose or tube 55 is connected with the head of the cylinder 50 above the piston to supply air pressure thereto for forcing the piston in its power stroke rearwardly to close the press. The air hose 55 is connected through a master valve 61 with a control manual hereinafter described.

When the piston 52 pushes outwardly on its power stroke, the lever 25 swings clockwise on

its compound-motion pivot 35 (traveling fulcrum) carried on the lower end of the heavy-pressure toggle 31, 32. Consequently, the upper lever end 26 urges to the right, but the bearing pin 27 moves on its arc around the frame bearing 22, and the head 17 is carried down by its arm 19. The lever 25 therefore swings clockwise on one pivot 35 and its lower end simultaneously swing outwardly on its other pivot 21, as demonstrated in Figures 2, 3 and 4. That movement brings the pressing head 17 to its initially-closed position where the spring pad 16 resists further movement of the head. At this point, there still remains a substantially long portion of the power stroke of the piston 52 (Figure 4).

The pressure flowing through the air hose 55 rapidly builds up, so that the piston pushes toward the outer end of the cylinder without a pause to Figure 5 position. The bearing pin 27 undergoes substantially a straight down but short movement from Figure 4 to Figure 5, while the wrist pin 54 pushes rearwardly a considerable distance, and the toggle joint 33 moves toward a dead center line defined by the pivot centers 34 and 35, but does not pass therebeyond.

The link member 32, 41 initially acts (Figure 2 to Figure 4) as a means to carry and guide the thrust link 31 and the traveling fulcrum 35 so that the actuating lever 25 may fulcrum clockwise on the pivot 35 to preliminarily close the press against the tension of the counterbalancing spring 37; and thereafter (Figure 4 to Figure 5) the toggle 31, 32 more particularly functions as a heavy-pressure leverage by the straightening action of the toggle toward a straight line to produce a thrust through its straightening knee joint 33 while straightening to effect final heavy jaw compression as the toggle links 31 and 32 straighten to a point where the motor piston 52 stalls against the resistance of the buck 15. During preliminary closing, the upper link 31 swings through a rather large angle (say about 60 to 70 degrees) on its frame pivot 34 since it is merely idling and not called upon to exert a thrust, whereas during final movement the link 31 swings through a smaller angle (say about 40 to 45 degrees) and thereby amplifies the force-applying function needed at that time to thrust and produce heavy jaw compression.

In all, the thrusting link 31 swings through an angular distance of a hundred degrees more or less, without its knee joint 33 passing dead center position. Inasmuch as the final pressure movement of the head (Figure 4 to Figure 5) is through a short distance, a toggle formed of short links has its advantages, delivers greater thrust, and occupies less space. It is unnecessary to have long and cumbersome toggle links occupying considerable operating space when the initial closing of the press is not a power consuming operation of great magnitude and can be accomplished by a direct acting lever 25 having a low ratio of mechanical advantage.

Figures 6 and 7 show the same heavy-pressure toggle leverage as heretofore described, but in a more advanced form to more nearly show the principle of the commercial construction, and more particularly to show a new crank-operating counterbalancing means to open the press. The same reference numbers are applied to the parts as heretofore described, except for the additional companion or secondary elements now introduced and explained.

The previously described arm 36 has a com-

panion counterbalancing arm 36^a which is also integral or fixed with the previously described short toggle link 31, these three members taking the form of a fork, as shown (Figure 7) from the rear of the press. A companion spring 37^a has its upper end attached to a pin 38^a carried on the arm 36^a and the lower end thereof is attached to the frame at 39^a. The two counterbalancing arms 36 and 36^a are made in the form of two spaced crank arms, with the bearing 9 mounted between them, and the frame bearing 34 acting as a crank bearing. The pins 33 and 33^a for the two springs act as crank pins against which the springs exert a rotative force.

It is noted that the secondary crank arm 33^a is shorter than the first arm 33. Furthermore, these two arms 36 and 36^a are offset from each other a substantial angular distance or some 60 to 80 degrees, so the two springs 37 and 37^a equalize each other and thereby do not work against the last portion of the power stroke of the motor (Figures 4 and 5) when the press is going under heavy pressure. Since the tension of the two springs 37 and 37^a is nearly the same, the longer crank arm 36 stretches the spring 37 to apply a counter-clockwise torque somewhat greater than the shorter spring 37^a. This double-spring counterbalance is built as an integral part into the heavy-pressure leverage 31, 32 and is efficient and smooth in its operation. This spring means acts directly upon the toggle joint 33 to collapse the links 31 and 32 and return them to normally open-press position when the air pressure is exhausted from the cylinder 59, thereby lifting the ironing head 17 to wide open position. Also, the two crank arms 36 and 36^a provide a method of installing multiple springs to open the press. Two sets of twin springs are sometimes used, two parallel springs in position at 37 and two at 37^a, thus providing four springs. Multi-counterbalancing springs are sometimes preferred so as to distribute the opening force among several springs to obtain an easier stretching action.

When the resisting spring padding 16 is under final ironing compression (Figure 5), a great reaction is built up against the head 17. The spring padding 16 therefore aids in initiating the opening movement of the head 17 when the motor means 50 is deenergized and releases the thrust from the toggle 31, 32. The reaction in the spring padding 16, with the tension of the spring means 37 and 37^a, quickly starts the opening movement of the press. After the crank pin 38^a swings counter-clockwise to the left of the crank bearing 34, it follows that the secondary spring 37^a also applies torque around that bearing and aids the spring 37 in returning and holding the press to its wide-open position.

The guide link 41 possesses additional functions which impart an improved mode of operation to the heavy-pressure leverage 31, 32 which for convenience may be termed a toggle, although it functions wholly different from the conventional toggle. Another viewpoint is that the linkage 31, 32 may be termed a variable-stroke crank and has been thus called from time to time during the comparatively long period this invention has been under development. Whatever that may be, it is now explained that the element or projecting guide arm 41 itself constitutes a toggle control or governor which, in its sequential action from Figures 2 to 5, acts to vary the stroke of the toggle or crank means 31, 32. This reference to a variable-stroke crank means is made of course to the two short swing links 31 and 32

throughout Figures 1 to 7, and is not to be confused with the spring counterbalance crank arms 36 and 36^a in Figures 6 and 7.

There is another toggle action to be noted and it likewise is controlled by the leverage variator means 41, 43. Reference is now made to pivots 27 and 34. By drawing a line through their centers it will be observed that pivot 35 does not pass that line when the press is under final pressure in Figure 5. The pivot 35 moves to the left rather rapidly, but the link 41 continues to so reset and hasten the toggle joint 33 to the left as to rapidly increase the distance from the frame bearing 34 down to the compound-motion pivot 35 traveling downwardly, whereby the latter does not pass dead center defined by a line extended through the pivots 27 and 34. Consequently, what may be said to be an inverted toggle link 25, is so arranged that it operatively depends from two pivots 27 and 35, the latter of which cannot lock past dead center because of the amplitude variator 41, 43.

Another feature of this invention is noted by study of Figure 5. Here the press is exerting its maximum pressure and is standing under strain. The operating leverage mechanism and its pivots are not only compactly arranged for structural unity, but are so placed as to most effectively exert the pressure forces and expend same in compressing the buck pad 16. It will be observed that there are three pivots 34, 22 and 27 lying within the arc of a circle which if extended pass approximately midway through the press jaws. In Figure 5, the center for a compass to draw this circular force path will be found by test to be slightly above and to the right of the reference number 9. This arrangement is found to be an advantage, in that the major portion of the pressure load sustained by the machine, while standing under final heavy pressure, is concentrated within a small space or area near the top of the machine adjacent the sturdy frame top or cover 6. The forces react and arch the circle in question and attain a static balance on the work being ironed between the press jaws by reason of the particular placement of the three main bearing points 34, 22 and 27.

The thrust circle or power circle feature just described is further illustrated in Figure 13 where the reference number 127 also locates the center of the thrust circle passing through the center of the closed press jaws and through the three main bearings 111, 22 and 27. Thus the major strain under which the press remains finally closed is carried by the frame top 109 and upstanding horns 5 which are integral and best qualified to carry such a load. Thus the lighter weight frame housing 2, 3 is not unduly stressed.

The high-power stationary cam-leverage shown in Figure 8

This view features a stationary cam type of heavy-pressure leverage for guiding the traveling fulcrum 35. The press construction may be the same throughout, and the same reference numbers are used, except for this modified cam and roller leverage substituted for the toggle leverage 31, 32 heretofore described.

A press-opening or counterbalancing spring 57 has its actuating end attached to the lower end 28 of the lever 25 by the wrist pin 54, while its upper end is attached to the top 6 of the press frame as shown. The spring is set at an angle to exert an upwardly forward pull on the lever 25 to raise the movable pressing head 17.

A cam track 53 is held adjustably mounted on a stationary-frame pivot 59. The cam track has a substantially vertical run 60 and a rear horizontal run 61. A roller 62 is journalled upon the compound-motion pivot or traveling fulcrum and is confined in the cam run 60, 61 for vertical and lateral travel therein. The vertical cam run 60 supports and guides the lever 25 while it fulcrums on its roller pivot 35 to exert an initial-closing force on the movable head 17.

An adjusting handwheel 63 and screw is adapted to thread in and out a swivel nut mounted in the end of the cam track 53 and is similar to the adjustment for the bell crank 45. The rear end of the horizontal run 61 of the cam track is set downwardly by the handwheel 63 to produce a down pull on the lever 25. The cam run 61 can be adjusted to compensate for the thickness of the buck pad 16, and to regulate the final-heavy pressure between the coacting press jaws.

It is noted that the compound-motion pivot 35 in both forms (Figure 1 and Figure 8) is adapted to undergo substantially the same angular movement. This comes about by reason of the fact that the lower lever end 28 first fulcrums clockwise on its compound-motion pivot 35, in either form of heavy-pressure leverage, to urge forwardly against the upper pin 27, whereupon said lever 25 starts downwardly (although still fulcruming on pivot 35) to complete the initial head-closing action, and finally its lower end pendently swings far outwardly on its upper bearing pin 27.

The foregoing new mode of operation is an efficient one because the motor 50 first uses the upper long lever arm (portion 25 to 26) above the arm 29 to attain a relatively fast closing speed. Thereafter a large amplification of the force exerted by the lever 25 is accomplished, greatly stepped up, by resolving its fulcruming action on the pivot 35 into an outwardly swinging motion, pendently, on the upper pin 27. That motion of the lever is resolved into a downward pull exerted on the head arm 19 by the cam run 61.

The guiding or variator linkage 44, 43 heretofore explained, and the vertical cam run 60 here discussed, alike performs a guiding function for the lever 25 while it is fulcruming on its pivot 35 and until the further travel of the head 17 is resisted by the buck padding 16. Thereupon, the heavy-pressure toggle 31, 32, and the horizontal cam run 61, alike exert a powerful down pull on the lever 25 and its upper bearing pin 27, since the lever 25 no longer fulcrums on the pivot 35 but swings pendently from the head-carrying arm 19 and pulls downwardly thereon.

The motor means and its control shown in Figure 11

This organization is shown in diagrammatic form, the motor means 50 thereof having been described. The aforementioned air hose 55 connects with the central part of an automatic master-control valve body or housing 67 disposed in the lower part of the machine frame. A main air-feed or pipe line 68, from a source of motive fluid or compressed air, connects directly with the top of the master valve 67. After this master valve automatically opens, the compressed air, under full and unrestricted line pressure and volume from the source pipe 68, flows directly through the air hose 55 into the cylinder 52, without passing through a restricted manual-control motor-starting valve means now briefly explained.

Any suitable pneumatic control may be used

for starting the motor means 50 and initially closing the press (Figure 4), and one example of such control is necessarily shown herein since it cooperates with a new automatic control for the motor as a feature of this press. A known form of two-hand control is selected as a motor-starting valve in order to illustrate the feature in question. A left-hand button 69 is mounted at the front of the press table, while a right-hand button 70 is spaced to the right thereof although not seen in the side view (Figure 1) since it is behind the button 69. The operator must depress both buttons 69 and 70 and hold them down with both hands to start the motor means 50 and keep it energized until the pressing head 17 swings through the danger zone (Figure 3) and has reached the buck (Figure 4), whereupon the operator safely releases both buttons. The master valve 67 will be shown to then automatically keep the motor in an energized state by holding open the main air line 55, 68 to maintain live air pressure on the piston 52. Doing so holds the press jaws sealed tight under compression and continues to urge the head 17 against the yielding pad throughout the ironing operation. This is due to the fact that after the piston 52 passes the port 89 the air passes from the cylinder through the pipe 90 and deflects the diaphragm 92 upward holding the valve head 91 open.

A branch air tube 72 has one end connected to the feed pipe 68 and its other end connected with a combination inlet and exhaust valve body 73 which is one of the two-hand valves, and it is operated by the button 69. An air tube 74 connects the valve 73 with a chamber 75 within the master valve 67; and an exhaust tube 76 connects the chamber 75 with an exhaust valve body 77 which is the other two-hand valve, and it is operated by the other button 70. The valve body 77 has a normally open exhaust valve with stem 78 adapted to be closed by the button 70 to shut an exhaust port 79 and thereby block off the air tube 76 so that air flowing into the chamber 75 of the master valve will not escape to atmosphere. In this way, the air pressure flowing downwardly through the tube 74 is directed upwardly through the air hose 55 into the cylinder.

The button 69 is depressed to thrust a valve stem 80 inwardly, this stem being common to a normally-closed intake-valve head 81 and a normally-open exhaust-valve head 82. That action reverses the valve unit 81, 82 against a spring 83 normally holding it in closed-press position (Figure 11), so that the intake 81 is now open, and the exhaust 82 is closed. Hence an exhaust port 84 is shut off from the branch 72, so that the latter opens directly into the air tube 74 connected with the valve body 73 between the opposed seats of the two valve heads 81 and 82.

A throttling valve 86 is included in the branch tube 72 between the feed pipe 68 and the valve 73. This throttling valve 86 has a well known screw threaded needle valve or stem 87 with a handwheel for adjusting it. The needle valve 87 can be screwed in and out to regulate the size of the conventional port shown in the valve body 86 by which to restrict and regulate the initial flow of air pressure from the branch tube 72 into the air tube 74 and thence through the air hose 55 to the cylinder 52 to start the piston 52. The high-pressure air from the feed pipe 68 through the pipes 72, 74 is preferably reduced by the hand valve 87 in order to appropriately regulate the speed of the piston 52 and hence the closing action of the pressing head 17. The reducing

needle valve 87 is adjusted in accordance with conditions, such as the air pressure available in the feed pipe 68 and the personal desire of the operator.

On the other hand, full line pressure from the feed pipe 68 is desirable at the moment the head 17 reaches the buck (Figure 4) so that no pause in movement occurs by reason of the resistance offered by the pad 16. Quick and full line pressure compensates for the drop in pressure in the cylinder 50, occasioned by the rapid outstroke of the piston 52, and prevents the piston from hesitating when the head first meets the resistance of the pad.

The operator depresses both buttons 69 and 70 and starts the motor piston 52 on its outer stroke toward a port 89 which is not uncovered by the piston 52 until the head 17 has passed through the danger zone and reaches its initially-closed (Figure 4) position. It will be borne in mind that the push button 69, when depressed, opens the normally closed intake valve head 81 and closes the normally open exhaust valve head 82, and that the push button 70, when depressed, closes a normally open exhaust valve, and also that the release lever 99 when operated, opens a normally closed exhaust valve head 100, which exhausts the air from the diaphragm chamber 91, permitting the valve 94 to return to its normal position, wherein the head 97 is closed. When the port 89 is uncovered by the piston 52, the air pressure in the cylinder 50 then flows through a diaphragm-feed hose 90 into a housing 91 and deflects a diaphragm 92 upwardly. The diaphragm 92 pushes on a stem 93 to close a master-exhaust valve 94 against its seat 95. The upward movement of this valve 94 in turn pushes on a stem 96 and opens a normally-closed master-intake valve 97.

Air pressure now by-passes the branch 72 and flows directly from the feed pipe 68 past the open intake 97 and into the air hose 55. Inasmuch as the valve head 94 is now closed against its upper seat 95, the air pressure from feed pipe 68 cannot escape to atmosphere through the exhaust tube 76 and its open valve 71. A spring 98 normally seats the master-intake valve 97 and holds the exhaust valve 94 down away from its seat 95. The thrust of the diaphragm 92, however, is adequate to compress the spring 98 and thereby reverse this unit-valve setting from Figure 11 position when the piston 52 uncovers the cylinder port 89. The spring 98 restores the master valve means to open-press position as shown, and deflects the diaphragm 92 downwardly when the pressure is relieved from the diaphragm chamber 91, and thereby deenergizes the motor 50, the means for which will now be described.

The cylinder port 89, in conjunction with the master valve 67, by-passes or cuts out the motor-starting branch line 72, 74 with its throttling valve 86 and two-hand control valve 73, doing so just as the pressing head 17 meets the resistance of the padded buck 15, 16. The then instant application of full air flow, unrestricted as to volume and pressure, coming directly from the feed pipe 68, raises the pressure to the cylinder 50 so as to continue the power stroke of the piston. Without this by-passing feature, the head 17 would pause when it reached the buck until the air pressure had built up in the cylinder 50, but my new control arrangement of the air lines provides for a steady piston stroke until the compression of the buck stalls the motor (Figure 5) under maximum ironing pressure.

A simple form of press-opening trigger-release manual 99 is mounted on the table, say on the front flange 7 thereof conveniently under the two-hand control valves 69 and 70. This trigger release 99 may be pivoted on a valve body 100 having a large exhaust port 101 normally closed by an exhaust valve head with stem 102. A spring keeps the valve 102 seated to normally close the exhaust port 101 and keep the trigger 99 in down position. This press-opening exhaust valve 100 is connected through an exhaust tube 103 with the diaphragm chamber 91.

By lifting the trigger 99, the valve 102 is thrust inwardly against the seating pressure of the spring shown, and the large exhaust port 101 instantly vents the diaphragm chamber 91 to atmosphere through the tube 103. The outlet through the exhaust port 101 is somewhat larger than the cylinder port 89, so that a drop in pressure instantly occurs in the diaphragm chamber 91 when the trigger 99 is lifted. The master valve spring 98 then snaps the intake valve 97 closed and exhaust valve 94 open (Figure 11 position) with the result that the air from the cylinder 50 rapidly exhausts back through the air hose 55 and out through the exhaust tube 76 and port 79 in the valve body 71. The springs 37 and 37a then open the press as heretofore explained.

Briefly upon depression of both push buttons 69, 70, air passes from the main line 68 through pipe 72 and pressure reducing valve therein, to valve casing 73, past the open intake valve head 81, through pipe 74, to the valve casing 67, thence through pipe 55 to the cylinder 50, actuating the piston therein on its power stroke. Because the valve head operated by the push button 70 is closed, the air can not exhaust out through the pipe 76 from the valve casing 67. The air can not pass from the main pipe 68 to the cylinder, because the valve 97 is closed. When the piston 52 on its power stroke passes the port 89, the air then passes from the cylinder through pipe 90 into the diaphragm chamber 91 actuating the diaphragm 92 to close valve head 94 against its seat 95 and open valve head 96 so that now air can flow from the pipe 68 past the open valve head 97 and through pipe 55 to the cylinder. The air can not exhaust from the pipe 90 out through pipe 103 and release valve 100 because the valve head in the casing 100 is closed. Thus because of the reducing valve 86, the press moves toward closed position under reduced air pressure but goes under final pressure under full or heavy air pressure. Operating of the release valve lever 99 to open the exhaust valve head in the casing 100 exhausts the pressure from the diaphragm 91, permitting the valve head 97 to close and cut off the air pressure, and as the operator has some time previously released the buttons 69, 70, the valves operated thereby are in their normal position. Thus the operator holds the push buttons 69, 70 depressed until the piston passes the port 89 at which time the button 69 can be released and the press will remain closed, due to the air pressure in the diaphragm chamber 91. It will remain closed until the release lever 99 is open.

The swinging-cam high-power leverage with its variator and hydraulic speed governor shown in Figures 12 thru 16

Further explanation is now made of the first form of the leverage variator shown in the previous views, but more particularly of a new form of my heavy-pressure variable-stroke leverage,

together with a hydraulic speed governor to be explained in the next topic.

This new leverage (Figures 12 through 16) is the continuing subject matter based upon my earlier application Ser. No. 104,672 for patent, and it is broadly covered thereby.

The somewhat erratic head action that otherwise might result is smoothed out and coordinated with the motor means by the full-automatic variable-stroke heavy-pressure leverage under the control of the restricted-radius leverage variator 41 shown in the previous views. But the whole combination is now further improved in certain particulars by making it in the form of a free-action or unrestricted leverage variator shown in Figures 12 and 13 as a swinging cam 118. The motion of this camming variator 118 is capable of control to a nicety because it is not under the restrictive action of the radius link 43 captive on its fixed center 44, as shown in the previous views.

In presenting this modified or improved form of the invention shown in the new views herewith, it is assumed that the reader now has knowledge of the laundry press construction and operation heretofore explained, and more particularly of the form shown in Figures 1 through 7. Those views show a variable-stroke heavy-pressure leverage of the linkage type comprising what may be called toggle links 31 and 32 which are under the control of the leverage governor or what may be termed the leverage coordinator or variator device 41. The front end thereof at pivot 42 is seen to be operatively restricted by a radius link 43 to an arcuate travel about the frame pivot 44. For that reason it has limitations in its leverage-governing or varying action which are now found not to be of maximum efficiency. Those limitations are now overcome by adopting my new cam and roller variator 118 shown in Figures 12 and 13 because its motion is controlled by a cam track calculated to a nicety and engineered to accommodate the given factors met with in efficiently driving the ironing head with a high-speed fluid-pressure single-cylinder motor.

Reference is first made to the previous views (Figures 1 through 7) and to part numbers therein indicated at 9, 31, 32, 41, 43 and also their pivot bearings for the purpose of explaining that they are the particular elements or parts therein shown which have now been modified in construction and mode of operation and are now designated by new part numbers in the description of Figures 12 and 13 to follow. The same reference numbers are used here in Figures 12 and 13 for those machine parts which are duplicates in the previous views. Therefore, new reference numbers are used only on the new parts now explained.

A counterbalancing coil spring or springs 105 has its lower end attached to a pin or frame pivot 106 and its upper end to a pull pivot 107 on the rear of the head-carrying arm 19, 21. A longer spring is used here, than the previous spring 31, for attaining more elasticity and less resistance throughout the long pull of a full-automatic press-closing action. One spring 105 is shown but in some cases two or more are used, depending upon the size and weight of the ironing head 17. This spring means 105 is mounted within the spaced upright frame walls 2 and extends alongside the pull lever 25. Sometimes two or even more springs are used by placing one or more on each side of the pull lever. The spring serves to open the press after the air pressure

exhausts from the motor means 50 by manually lifting the trigger valve 99 (Figure 11), and it holds the press in normally open position. The counterbalancing springs are made strong enough to quickly open the head and expose the ironed work on the buck 15 so the operator may remove it therefrom and make another lay of damp work to be ironed.

A heavy-pressure leverage bearing bracket 103 depends from the upper frame cover or cap 109 at the rear of the press and is somewhat like the previous bracket 9. Preferably this bracket means is formed integrally with a frame cover 109. The latter extends from the front plate 3 rearwardly to provide a support for the buck 15 and then upwardly adjacent the frame pivot 22 where the head-carrying arm 19 is pivotally mounted between the two upstanding frame brackets or horns 5. It is preferable to form the spaced upstanding frame horns 5 integrally with the top plate 109 by which to compactly assemble in a small space the parts carrying the major load and thrust delivered to the ironing pad 16.

The bearing bracket 108 has an integral lug in the form of a stop or shoulder 110 concentric with a heavy-leverage pivot or shaft 111 journalled to rock in the frame bracket 108. In fact this bracket means preferably comprises two spaced parallel frame parts 108 integral with the frame top plate 109 by which the variable-stroke heavy-pressure leverage is interconnected between said press frame bracket 108 and the motion-transmitting means 19, 25.

A short radius arm or what may be called a toggle link 112 may have its upper end pivoted on the frame bearing 111, but the toggle arm 112 is actually pinned or keyed to shaft 111 so as to rock it in the frame bearing 108; this for the purpose of establishing a direct drive of the hydraulic speed governor (Figures 14 through 16) later described. This toggle link 112 also has an integral stop or shoulder 113 likewise formed concentric with the pivot 111 and is adapted to swing clockwise (Figures 12 and 13) and come to rest and hence stop against the stationary frame shoulder 110. The free end of this arm carries a pivot 114 somewhat like the toggle joint 33 in the first views of the drawings. Then there is provided a second pivot 115 on the reach arm 29 of the compound-motion pull lever 25 the same way as the pivot 35 in the former views. A link 116 operatively connects the two pivots 114 and 115.

If it were not for my leverage differential or variator 41 and its new successor 118 in Figures 12 and 13 herewith, the two links 112 and 116 taken together might comprise an ordinary toggle, but the action thereof is so entirely different from that of a conventional toggle that this new means might be called a variable-stroke partial-turn crank. However, this part 116 may be referred to as one link of a toggle since it connects the two pivots 114 and 115, although it is actually the rear or left-hand portion of the new leverage variator 118 to be described. The link 116 may be made in the form of a fork so as to receive the lower end of the short arm 112 and the upper end of the longer arm 29. Another preferred construction is a forked formation on the members 112 and 29 so as to receive therebetween the short link 116.

The toggle governor or what may be called a leverage variator, motion regulator or guide means 118 is integrally formed with the toggle link 116 and extends forwardly within the press

frame and, because it is cam controlled possesses an improved mode of operation over its predecessor 41 in the previous views. This cam-type leverage variator 118 so modifies or guides the action of the toggle links 112 and 116 as to produce a new element in full-automatic pressing machine leverages. It may be said that alone the two operating links 112 and 116 comprise a toggle, but this coupled-in variator control member 118 is believed to not only make thereof a new toggle per se, but also constitutes a new combination. Thus, either variator 41 or 118, coupled into the links 112 and 116, forms a toggle wholly different from the generally accepted form. Insofar as it is structurally and operationally known and understood, aside from the mere names of these parts, singly or in combination, this new arrangement affords a marked improvement in laundry-press leverages.

It will be seen that the leverage variator itself is made integral with the link 116, but for convenience one number points to its left end as the coupling portion 116 between the pivots 114 and 115, while another number 118 points to the right-hand end as the leverage governor portion having an automatic stroke-regulating and controlling action over high-power toggle 112, 116 as well as the stroke motor piston 53.

The leverage variator 118 has formed in its outer or forward end a long downwardly sloping press-closing cam-run 119 which joins a short upwardly sloping heavy-pressure cam-run 120. The latter portion 120 is more nearly horizontal when the press is open (Figure 12) but assumes an up-turned position (Figure 13) when the press is closed. The press-closing cam-run 119 and the heavy-pressure cam-run 120 are joined by a cam-turn 121. The first and longer cam-run 119, from its upper left end down to the turn 121, is defined by a radial curve, the center of which is located just beyond the lower edge of the member 118. At the same time, the second and shorter cam-run 120 is defined by a shorter radial curve, extending upwardly and to the right, the center of which is just beyond the upper edge of the member 118. The two cam curvatures appear here in small scale, but become more pronounced in larger scale and when observed in the full-size machine.

The leverage variator or differential-cam arm 118 is confined on a cam roller 122 journaled upon the bell crank heretofore numbered 45, but now indicated at 123 in Figures 12 and 13. The roller 122 functions a frame bearing since it is held in a stationary position by the bell crank lever 123 adjustably anchored to the press frame. This lever is pivoted on the inside front of the press at 124 by the frame bracket 10. One end of the lever 123 mounts the cam roller 122 and its other end is susceptible to a limited adjusting movement about the frame pivot 124 for the purpose of varying the up and down position of the cam roller 122. This adjustment is preferably used only by the manufacturer of this press for properly setting its ironing head and the heavy-pressure leverage to a predetermined position closely gauged and checked after the press is assembled and the padding 16 is in place on the buck. Such adjustment once made is permanently fixed and remains in that position after the presses go into service unless maladjusted by inexperienced hands.

The upper end of the bell crank lever 123 is shown as provided with any suitable means for adjustably anchoring it to the frame and for

making the above explained adjustment at the factory. One convenient device for this may be a fork at the upper end of the bell crank to receive a swivel nut 125, into which is screwed an adjusting bolt 126 having a lock nut on the outside of the press frame 3 and a collar fixed to this headed bolt 126 on the inside thereof. After the press is assembled and the pad 13 is installed, a wrench is used on the bolt 126 and its lock nut 10 for the purpose of very finely setting the bell crank 123 about its frame pivot 124. Thus the position of cam roller 122 is carefully adjusted up or down so that it correspondingly moves the front end of the leverage variator 118, and hence 15 moves the motion-transmitting means 25, 19 interconnected between the motor 59 and head 17, to apply that predetermined ironing compression between the head and buck as best suited for the particular type and model of press when it goes 20 into service.

The above-described adjustment to attain the requisite ironing pressure is set into the machine at the factory as a part of its construction and is inherent therein. The purchaser or user of 25 the press is not required to manipulate the device 126 or change its adjustment as originally made on the machine by a factory expert. The adjustment hand-wheel 48 shown in the previous views is for the same purpose, but it is found that through mistaken impression some operators may get this new press out of adjustment by turning the conveniently arranged hand-wheel 48. So it is found at one time preferable to remove it and substitute this smaller adjustment screw head 126 which, being up under the table of the press and not a convenient hand-wheel, is not seen and is not so readily adjustable by a curious operator, and is less likely to be tampered with. On the other hand, some 30 users are not satisfied unless they can adjust their press, so that in the end a fairly accessible hand-adjusting means may be better.

In coming to the description of some of the 35 operating characteristics of this new press, reference may be made to previous views, particularly Figures 2 to 4 showing a motion study. It is seen that the roller 122 is normally at rest adjacent the cam-turn 121 when the press is open (Figure 12) and lies within the long cam-run 119. When air pressure is admitted to the front end of the cylinder 50, the lower end 22 of the main lever 25 then tilts rearwardly on its pivot 35 or 115.

Now the ironing head 17 starts downwardly 40 around its pivot center 22, thus forcing the fulcrum point 115 downwardly, and the head-closing cam-run 119 first runs downwardly to the right on the roller 122 for the major travel (Figures 2 to 4) of the head 17 towards the buck pad 16. During that travel, the action of the first cam-run 119 rapidly shifts the toggle joint 114 clockwise to the left (and thus runs or advances this center pivot or toggle joint 114 in between the outer pivots 111 and 115) and thereby differentially increases (steps up) the amplitude or stroke of the leverage or crank means 112 and 116 acting at this time (Figures 2 to 4) as a mere guide for the lever 25. In other words, the low-power lever 25 is carrying with it the high-power leverage 112, 116, and the leverage variator 118 is accelerating the traveling fulcrum 115 by reason of the progressive decrease of the mechanical advantage of the low-power leverage 19, 25 which hastens the head-closing motion and economizes on the stroke of the piston 52.

Consequently, the toggle joint 114 is hastened counterclockwise around its lower pivot 115 simultaneously with the clockwise motion of the upper link 112, by reason of the variator 118 guided by its cam and roller means. This toggle joint 114 is advanced to the left (note the same pivot 33 in Figure 2) over the pivot 115, thereby pushing downwardly on the latter, and drawing downwardly on the lever 25 and head 17, doing so without undue expenditure of the motor piston stroke.

Just before the short link 112 reaches its down position (Figure 13) it begins to amplify the power of the motor means 52 and apply final pressure before its stop 113 reaches the frame shoulder stop 110. This is due to the fact that the ironing head 17 has reached its heavy pressure position and the motor piston 52 has stalled by reason of the resistance of the buck padding 16. When the head reaches the buck (Figure 4), the leverage variator 118 reverses and acts somewhat the same as link 41 (compare its Figure 4 position to Figure 3) and now travels reversely upwardly to the left until the cam-turn 121 this time comes all the way back to the roller 122, at which position the ironing head is taking up the softness or fluffy slack in the spring padding 16. The cam-turn 121 now actually traverses the roller 122 (goes around the corner) and the second cam-run 120 travels slowly to the left and downwardly on the roller while the high-power leverage 112, 116 is urging the head from Figure 4 to Figure 5 position into final-jaw compression. The piston 52 finally stalls under power, but maintains its forceful urge on the head 17 to inch it down for any give in the padding 16. However, the toggle stop means 110, 113 do not yet engage since it is preferred that the link 112 remain free to urge clockwise as the motor piston 52 urges the head tighter on the buck pad 16.

At the inception of head motion, that is, in starting the head 17 downwardly by overcoming its inertia, the motor 50 uses its first power impulse to directly fulcrum the low-power lever 25 on the pivot 35 or 115, which is to say that the motor acts directly on the lever 25, and not on the high-power leverage 112, 116; the latter merely follows the lever 25. The leverage ratio inherent in the low-power motion-transmitting means 19, 25 itself is alone sufficient to attain an easy start of the head. Starting the head is not resisted by the high-power leverage 112, 116. Thereafter, the continued down motion of the head does not require much power, in fact only enough to stretch the counter-balancing springs 37 or 105 is all that is required.

The high-power leverage 31, 32 as well as 112, 116, at the start of the motor piston 52 and while the head is swinging toward the buck (Figures 2 to 4), does not resist the thrust of the piston but merely idles and follows downwardly with the lever 25. Thus the motive force applied at the wrist pin 54 acts directly to fulcrum the lever 25 upon the pivot 35 or 115, to effect the long head-closing motion, and the high-power leverage during that time (Figures 2 to 4) acts to accelerate the down motion of the lever 25 and decelerate the stroke of the piston 52, so as to conserve the latter until the end, that is (Figures 4 to 5) for compressing the padding 16 under final ironing pressure. Easier and less sudden head starting is now attained with this motion-transmitting means, in the form of a new compound leverage, than in conventional laundry presses having a single-cylinder operatively con-

nected with the high-power side of a compound leverage.

When the press first starts closing, the cam-run 119 runs down to the right on the roller 122 and the outer free end of the leverage variator 118 swings counter-clockwise on the roller, but by the time the head reaches the buck (Figure 4), the first cam-run has reversed its direction and returned the cam-turn 121 to the roller. As the cam-turn 121 now goes around and past the roller, the ironing head begins to go under compression against the pad 16, and the outer and short cam-run 120 so controls and works with the decelerating leverage 112, 116 that the piston 52 of the motor now increases the length of its stroke proportionately over the reduced down travel of the fulcrum 115 as to impart a short movement at a reduced leverage ratio to the ironing head, due to the straightening movement of the toggle links 112, 116 during the comparatively long travel of the piston 52.

The cam and roller means 122 sustain a small proportion of the total bearing load or thrust and are not subject to the considerable wear and tear experienced with conventional presses having direct-acting cam leverages. Only a small fractional part of the total load carried by the high-power leverage 112, 116 is transmitted to the cam run and roller 122. Minimum wear occurs and the mechanism gains increased life.

Either of the leverage variators 41 or 118 pays out the stroke of the piston 52 very sparingly, from just after the head 17 is started, on through Figure 3 and to Figure 4 position. Thus the variator 118 saves back the power stroke of the motor piston 52 until Figure 4 position, whereupon the second cam-run 120 pays out very rapidly on the piston stroke. This action, of course, could not be attained by employing an ordinary toggle linkage, but is very largely accomplished by the restricted or captive link 43 regulating the movement of the leverage variator 41 in the first form of this invention, and now more efficiently accomplished to a nice degree by the contour of the cam-runs 119 and 120 in the new leverage variator 118. In short, the cam slot 119 and follower or pin 122 bring about approximately the same movements of the arm 118 and the toggle links 112 and 116 (Figure 12) as the link 43 brings about in the arm 41 and toggle links 31, 32 (Figure 1).

When the spring padding 16 on the buck wears down thin and loses some of its resiliency, this press produces the same ironing compression as 55 when the padding is new and fluffy and possesses its original resiliency. This is accomplished by the follow-up stroke of the piston 52 and the action of the compound leverage with its variator 41 or 118. Also, there is no toggle locking (over-centering) action during any stage of pad wear, and for the thinnest worn pad there always remains enough piston stroke to deliver the same jaw compression as when the pad is new and thick.

65 The pad 16 will recede under hard usage and lose its resiliency and thickness, but this leverage follows up (or here it follows down) that pad recession by urging the head 17 downwardly for any fractional diminishing of the original thickness of the pad. Consequently, this new compound leverage, actuated by a single motor means, produces uniform pressure and uniform ironing quality for all degrees of thickness of the padding 16. A new pad of the same make, thickness, and construction can be installed by the

operator on the press without altering the adjustment device 48 (Figure 1) or 126 (Figures 12 and 13). However, if the press user or operator puts on another type of pad, not conforming to the standard factory pad, then the adjusting lever 45 or 123 must be reset to this new padding condition.

When the air pressure is exhausted from the cylinder 50, the reaction and expansion of the spring padding 16 imparts an opening impulse to the press. Both counterbalancing springs 37 and 105 then readily act to carry either pivot 35 or 115 in a counter-clockwise return motion to open the press. This is true for any relative position of the ironing head from Figure 4 to Figure 5, and for any degree of pad wear and recession.

In the installation of a new pad 16 on the buck, as well as for other purposes of convenience, the toggle stop means 110, 113 merely prevents the toggle knee joint 114 from accidentally snapping too far to the left (Figure 13). The power of the press-opening spring 105, or other forces, might accidentally throw the toggle joint 114 so far beyond its normal travel as to make it hard to bring it back, and since that might occur when servicing or repairing the machine, the toggle stop 110, 113 is provided as a means to forestall that difficulty.

The press leverage with its built-in hydraulic governor shown in Figures 14, 15 and 16

In order to control the speed of the ironing head 17, and in particular render it possible to swing the head up and down at high velocity, without shock and strain upon the press, a combination speed controller and shock absorber is operatively connected in a direct manner with the press leverage in a new and efficient way. Ordinarily, I call this device the "hydraulic governor" for the press, and its two functions are believed to be accomplished by an improved mode of operation over conventional laundry-press practice. The construction of the hydraulic governor constitutes the subject matter of divisional application Serial Number 338,785, filed June 4, 1940.

It is to be noted, in the examples shown, that the hydraulic governor is directly connected to the main shaft carrying the high-power leverage, say the shaft 34 (Figures 1-7) or the shaft 111 (Figures 12-14) where, in these latter views, the hydraulic governor is now referred to and described. Consequently, the swinging toggle link 31 is to be fixed to the shaft 34 to rock it, and likewise the toggle link 112 is shown keyed or pinned at 129 to the high-power leverage shaft 111 to drive or rock the latter as an actuating medium for a hydraulic governor 130 now described. The high-power leverage shaft 34 or 111 has a large degree of rocking motion.

The swinging action of the high-power toggle leverage 31, 32 or 112, 116 acts to positively rock the shaft 34 or 111 within the frame bearings 8 or 168 as a power shaft to drive the governor 130. The shaft 111 is rocked clockwise by the motor piston 52 to close the ironing head 17, and it is reversely rocked counter-clockwise by the counterbalancing spring means 105 to open the press. It is important to note that the shaft 111 is directly coupled to the hydraulic governor 130. This governor acts to control the press-closing speed by holding the latter to a constant rate and thereby preventing any increased speed thereof throughout the fast-closing cycle, and it also acts to permit maximum opening

speed but checks the momentum of the latter and absorbs the shock at the end of the fast-opening cycle.

The hydraulic governor includes a stationary cylinder or block 130 mounted on the side of the press frame, as by screws 132 threading into bosses 133, pinion shaft 134 journaled in the upper part of the cylinder block 130 in position to come into alignment with the shaft 111 or 134. The shaft 134 has a coupling head 135 which mates with the coupling head 136 on the shaft 111 of the press. On the shaft 134 within the cylinder block 130 is mounted a pinion 138, this being located just beneath the cover 131 for the cylinder block. The pinion 138 meshes on opposite sides of its axis with racks provided on piston plungers which work in bores in the cylinder block 130. One of these plungers 139 is provided with a piston head 141 working in the cylinder 140 within the cylinder block 130. The other plunger 145 is provided with a piston head 146 working in another cylinder bore 147. During the rocking of the pinion 138, these plungers move in opposite directions relatively to each other. Suitable valves are located to control the flow of fluid into and out of the lower end of the cylinders from and to the interior of the cylinder block 130 which constitutes a reservoir. 142 designate the valve casings. These valve casings also carry adjustable throttle pins 143 and 148 respectively. As the subject matter of this hydraulic check forms no part of this invention but constitutes the subject matter of another application, it is sufficient to bear in mind, in so far as this invention is concerned, that the opening and closing movement of the press is governed by this hydraulic check through a high power shaft of the press mechanism, as the shaft 111.

In the operation and use of the press, the operator makes her lay of the damp laundered apparel or work piece upon the buck 16 in the usual way and then depresses the control buttons 69 and 70 (Figures 1 and 11) as previously explained, to energize the motor 50 and close the press. Any suitable form of motor means and control therefor can of course be employed in connection with the various features of this invention, so the air motor and its control are merely referred to here in an illustrative sense. The ironing head 17 remains under final heavy jaw compression until the work is ironed dry, whereupon the operator causes the press to open by any suitable opening control, as indicated at 99 (Figures 1 and 11).

In operation, the motor 50 delivers an outward thrust on the lower end 28 of the lever 25 which initially pivots the lever clockwise on the travelling fulcrum 115. This motion imparts a forward and down motion to the head arm pivot 27, with the result that the lever 25 undergoes a bodily shifting movement downwardly and clockwise, and at the same time begins to straighten the high-power toggle leverage 112, 116. As the latter straightens, the leverage variator 118 functions as previously explained to accelerate the downward motion of the travelling fulcrum 115 and in turn decelerates the stroke of the piston 52, thereby saving back part of the length of the latter for applying the greater force needed in going under final pressure (Figures 4 to 5).

Thus the motor means 50, or other form of actuator, initially acts directly upon the low-power leverage 19, 25 to swing the ironing head

17 down to the buck (Figures 1 to 4), and thereafter the motor further acts directly on the lever 25 to pull the head down through the high-power leverage 112, 116 into final pressing position. During this press-closing operation, the governor shaft 134 rocks clockwise to drive the speed-control piston 146 downwardly. The hydraulic piston 146 acts as a means to prevent the motor 50 from increasing the velocity of the ironing head and prevents the latter from exceeding the speed for which the hydraulic speed governor is set by its speed-control valve stem 148.

It is important to note, in the final straightening action (Figures 4 to 5) of the high-power leverage 31, 32 and 112, 116, that there is a deceleration of the travelling fulcrum 35 and 115. This reduced speed is due to the fact that as the high power-toggle straightens, its down-thrusting pivot 35 and 115 nears the limit of travel, and it is a natural characteristic of a toggle to slow down and thrust harder as it approaches its straightened limit. This slowing down decelerates the ironing head 17 as it approaches the buck, so that it goes under final pressure (Figures 4 to 5) without impacting the buck padding.

Observe, therefore, that the last portion of the down movement of the speed-governor piston 146 likewise is decelerated and no longer resists the power of the motor 50 so that the latter delivers a final high-power thrust to the head 17 without meeting any resistance from the hydraulic speed-control piston 146. This will be seen when it is understood that the oil freely escapes from the speed-control cylinder 147 without resisting the movement of the plunger for any slower speed of the latter than for that speed at which it is adjustably set by the valve stem 148.

Take the reverse operation, when the ironing head 17 is moving upwardly, then the hydraulic governor shaft 134 rocks counter-clockwise. The result is that the speed-control piston 146 moves idly upwardly, while the shock-absorber piston 141 travels downwardly to now perform its checking function.

In the general operation, upon operation of the manual control buttons 69, 70, the air passes into the cylinder 50 through the master valve 67 and the pipe 55, and upon actuation of the piston 52, the actuating lever 25 first swings rearward about the fulcrum 35 starting the head 17 in motion and moving it through a high leverage ratio in the long downward and forward portion of its arcuate path, to preliminarily close the press or bring the head down close to the work on the buck 15, or the padding 16 thereof. This high leverage ratio consists of the short arm of the lever from the pivot 54 to the fulcrum 35 and the long arm represented by a line from the fulcrum 35 to the pivot 21, the lever 25 being what for convenience might be called a floating C lever fulcrumed at the end of its lower arm. As the power is applied to the lower end of the lever 25, the lower end swings rearward and hence, the fulcrum 35 shifts. Owing to the fact that the head is moving in the downward and forward sweep of its arc of movement, the fulcrum of the lever is moved downward and slightly rearward due to the action of the piston. During this movement, illustrated in Figures 2, 3 and 4, the toggle links 31 and 32 are held folded, or cocked, or are held from straightening to any extent until the press head contacts or

encounters the resistance of the buck 12, as seen in Figure 4, and the fulcrum 35 moves downward while the toggle remains folded. As the power continues to be applied to the lever 25 to swing it rearward, the lever now swings about the pivot 21 and in so swinging, the variator 41 now straightens the toggle 31 and 32 to apply the power through a short reduced leverage ratio, pulling the lever 25 rectilinearly downwardly as a pull link and hence pulling the head 17 rectilinearly downwardly into final pressing position against the padding 16 on the lower buck 15, the mechanism automatically passing from the high ratio leverage into the low ratio toggle leverage easily and without shock, owing to the arrangement of the toggle. The so-called variator 41 functions to hold the toggle links folded, or cocked, during the preliminary closing.

In the form shown in Figures 1 to 6 inclusive, this variator, or toggle governor, or timer 41 is controlled in its movement by a link arrangement. That is, the arrangement of the links 43, 45, and these links are so arranged as to produce a resultant similar to the cam slot shown in Figure 8. That is, the shape of the cam slot 69, Figure 8 is such as to initially hold the fulcrum 35 from free rearward movement while the lever is free to swing rearward about the fulcrum, but permits the fulcrum to move downward as the press head swings from open position through the downward and forward position of its arc, into preliminary no pressure closed position, and then to force the fulcrum 35 downward while the lever 25 swings about the pivot 21 at its upper end and hence, to cause the lever 25 to act as a pull link and move the press head through the short, final pressure, upright portion of its arc of movement. The toggle links 31, 32 effect this same resultant movement indicated by the cam slot Figure 8. The cam slots 119, Figures 12 and 13, effect the same movements of the variator 41 as the link 41 and lever 45, Figure 1, to control the straightening of the toggle.

To open the press, the trigger 99 is operated to release the air from beneath the diaphragm 92, permitting the master valve to close the air line 68 and open the pipe 55 to the exhaust of air from the cylinder so that the press is free to open under the action of the counterbalancing springs resetting the actuating mechanism in starting position.

This invention is presented to fill a need for improvements in a textile ironing press. It is understood that various modifications in structure, as well as changes in mode of operation, assembly, and manner of use, may and often do occur to those skilled in the art, especially after benefiting from the teachings of an invention. Hence, it will be understood that this disclosure is illustrative of preferred means of embodying the invention in useful form by explaining the construction, operation and advantages thereof.

What is claimed is:

1. A power-operated textile press comprising a frame, a padded buck, and a pressing head adapted to move high above and to close down upon the buck; a low-power leverage operatively connected with the pressing head to swing the latter through its long movement in relation to the buck, a high-power leverage fixed on a rock shaft journaled in the frame, the low-power leverage being fulcrumed between its ends upon the high power leverage, the latter moving idly

with the low-power leverage during the long movement of the head; and a single actuating means, operatively interconnected between the frame and the low-power leverage, acting directly upon said low-power leverage to initially swing the pressing head from its wide open position down to the buck, and indirectly upon the high-power leverage to finally bring the latter out of its idling movement into a thrusting position to exert great force against the low-power leverage, thereby applying final-heavy pressure to the padded buck, in combination with a hydraulic governor anchored on the frame and operated by the rock shaft.

2. A variable motion transmitting means for a machine having closing and opening movements, including a frame and work-treating element movably mounted thereon, comprising a lever one end of which is operatively connected with the work-treating element, the other end of said lever being operatively connected with a power-producing means, and a movable-fulcrum means fixed on a rock shaft journaled in the frame and pivotally connected with the lever between its ends, whereby, at the beginning of the closing movement, the movable-fulcrum means acts on the lever to vary its leverage effort exerted on the work-treating element as the latter moves in relation to the frame, and the power-producing means thereby initially imparts high speed with a low force to the movable work-treating element and progressively reduces the speed and increases the force during the closing movement, until at the end of said closing movement the work-treating element is moving with great force under the action of the movable-fulcrum means which is transmitting all the force from the power-producing means to the work-treating element, in combination with a hydraulic governor fixed on the frame and operated by the rock shaft.

3. In a garment and laundry press, the combination of a frame, a stationary buck mounted on the frame, a press head mounted to move toward and from the buck in a downward and forward arcuate path with the upright portion of the arc extending at nearly a right angle to the pressing face of the buck, means for carrying and guiding the head in its movement, actuating mechanism comprising an upright lever pivotally connected at its upper end to said head carrying means, the lever having a fulcrum near its lower end arranged to permit the lever to swing about its fulcrum and shift downward during the arcuate closing of the press head, a prime mover connected to the lower portion of the lever, means to confine rearward shifting of the fulcrum during the rearward swinging of the lower end of the lever, including toggle links pivoted to each other and respectively to the frame and to the fulcrum, and means operated by the swinging movement of the lever to hold the toggle links folded and to straighten the same only when the press head reaches the upright portion of its arc of movement, said toggle and the fulcrum being arranged to straighten toward a substantially vertical line intersecting the pivotal connection between the upper end of the actuating lever and the head carrying means.

4. In combination in a garment and laundry press, a frame, a stationary buck mounted on the frame, a press head movable toward and from the buck in a downward and forward arcuate path with an upright portion of the arc extend-

ing at nearly a right angle to the pressing face of the buck, a head carrying arm pivoted to the frame in the rear of the buck, actuating mechanism comprising an upright lever pivotally connected to the head carrying arm between the pivot of the head carrying arm and the head, the lever having a shiftable fulcrum near its lower end and arranged to permit the lever to swing fore and aft about the axis of the fulcrum during the closing and opening movement of the press, a prime mover connected to the lower portion of the lever to swing the same about its fulcrum, means operating to control the shifting of the fulcrum downward during the rearward swinging movement of the lower end of the lever including toggle links pivoted to each other and respectively to the frame and the lever at the fulcrum thereof, the toggle links being folded when the press is open, and means operated by the swinging movement of the toggle successively to hold the links folded until the press head reaches the upright portion of its arc of movement and then straighten them, the pivotal points of the lever to the head carrying arm, of the arm to the frame and of the toggle link to the frame being located, when the press is closed, approximately in an orbit intersecting the intermediate portion of the head and the buck.

5. In combination in a garment and laundry press, a frame, a stationary buck mounted on the frame, a press head movable toward and from the buck in a downward and forward arcuate path with the upright portion of the arc extending at nearly a right angle to the pressing face of the buck, a head carrying arm pivoted to the frame in the rear of the buck, actuating mechanism comprising an upright lever pivotally connected to the head carrying arm between the pivot of the head carrying arm and the head, the lever having a fulcrum near its lower end and arranged to permit the lever to swing fore and aft about the axis of the fulcrum during the closing and opening movement of the press, a prime mover connected to the lower portion of the lever to swing the same about its fulcrum, means operating to control the shifting of the fulcrum downward during the rearward swinging movement of the lower end of the lever including toggle links pivoted to each other and respectively to the frame and the lever at the fulcrum thereof, the toggle links being folded when the press is open, and means operated by the swinging movement of the lever to successively hold the links folded until the press head reaches the upright portion of its arc of movement and then to straighten them, the pivotal points of the lever and the press carrying arm, of the arm and the frame, and of the toggle to the frame being located, when the press is closed, approximately in an orbit intersecting the intermediate portion of the head and the buck, the pivotal connections of the toggle to the frame and to the lever at the fulcrum point thereof being movable approximately into a straight upright line passing through the pivotal point between the lever and the head carrying arm, when the press is closed.

6. In a garment and laundry press, the combination of a frame, a stationary buck mounted on the frame, a press head mounted to move toward and from the buck in a downward and forward arcuate path with the upright portion of the arc extending at nearly a right angle to the pressing face of the buck, means for carrying and guiding the head in its movement, actuating mechanism comprising an upright lever pivotally

connected at its upper end to said head carrying means, the lever having a fulcrum near its lower end arranged to permit the lever to swing about its fulcrum and shift downward during the arcuate closing of the press head, a prime mover connected to the lower portion of the lever, means to confine rearward shifting of the fulcrum during the rearward swinging of the lower end of the lever, including toggle links pivoted to each other and respectively to the frame and to the fulcrum, a guide arm rigid with one of the toggle links, and motion varying connections between the guide arm and the frame to control the movement of the toggle links relative to each other and to time and effect the straightening of the toggle relative to the closing movement of the press by the lever.

7. In a garment and laundry press, the combination of a frame, a stationary buck mounted on the frame, a press head mounted to move toward and from the buck in a downward and forward arcuate path with the upright portion of the arc extending at nearly a right angle to the pressing face of the buck, means for carrying and guiding the head in its movement, actuating mechanism comprising an upright lever pivotally connected at its upper end to said head carrying means, the lever having a fulcrum near its lower end arranged to permit the lever to swing about its fulcrum and shift downward during the arcuate closing of the press head, a prime mover connected to the lower portion of the lever, means to confine rearward shifting of the fulcrum during the rearward swinging of the lower end of the lever, including toggle links pivoted to each other and respectively to the frame and to the fulcrum, a guide arm rigid with one of the toggle links, and motion varying connections between the guide arm and the frame including a link pivoted at one end to the guide arm and at its other end to a point fixed relative to the frame, the link extending at an angle to the lengthwise dimension of the guide arm.

8. In a garment and laundry press, the combination of a frame, a stationary buck mounted on the frame, a press head mounted to move toward and from the buck in a downward and forward arcuate path with the upright portion of the arc extending at nearly a right angle to the pressing face of the buck, means for carrying and guiding the head in its movement, actuating mechanism comprising an upright lever pivotally connected at its upper end to said head carrying means, the lever having a fulcrum near its lower end arranged to permit the lever to swing about its fulcrum and shift downward during the arcuate closing of the press head, a prime mover connected to the lower portion of the lever, means to confine rearward shifting of the fulcrum during the rearward swinging of the lower end of the lever, including toggle links pivoted to each other and respectively to the frame and to the fulcrum, a guide arm rigid with one of the toggle links, and motion varying connections between the guide arm and the frame including a cam run and follower coacting therewith, one being fixed relatively to the frame and the other on said guide arm.

9. In a garment and laundry press comprising a frame, a stationary buck mounted on the frame, a press head movable toward and from the buck in a downward and forward arcuate path with the upright portion of the path extending at nearly a right angle to the pressing face of the buck, and means for carrying and guiding the

head in its movement; the combination of actuating mechanism comprising an upright lever pivotally connected at its upper end to the head carrying means, a fulcrum for the lever spaced apart from the pivot arranged to permit the lever to swing fore and aft about the fulcrum, whereby the lever moves forwardly and rearwardly about its fulcrum, a prime mover connected to the lever at a point spaced from the fulcrum and the pivot of the lever and acting thereon to move the lever about its fulcrum and to swing the lever about its pivot, fulcrum guide means coacting with the fulcrum to successively cause the lever to move on its fulcrum during the closing of the press and to guide the fulcrum in a fore-and-aft and downwardly extending path, to swing the lever about the pivot at its upper end and to pull the lever downwardly so that it acts as a pull link during the final closing movement, and translate the rearward swinging movement of the lever into a downward pull link movement.

10. In a garment and laundry press comprising a frame, a stationary buck mounted on the frame, a press head movable toward and from the buck in a downward and forward arcuate path with the upright portion of the path extending at nearly a right angle to the pressing face of the buck, and means for carrying and guiding the head in its movement; the combination of actuating mechanism comprising an upright lever pivotally connected at its upper end to the head carrying means, a fulcrum for the lever spaced apart from the pivot and arranged to permit the lever to swing fore and aft about the fulcrum, whereby the lever moves forwardly and rearwardly about its fulcrum, a prime mover connected to the lever at a point spaced from the fulcrum and the pivot of the lever and acting on the lever to swing it about its fulcrum and about the pivot at its upper end, fulcrum guide means coacting with the fulcrum and operable during the closing of the press to successively cause the lever to fulcrum and act as a lever, and to guide the fulcrum in a fore-and-aft and downwardly extending path, swing the lever about the pivot at its upper end and force the fulcrum downward and act as a pull link while the lever is swinging about the pivotal connection at its upper end during the final closing of the press.

11. In a garment and laundry press comprising a frame, a stationary buck mounted on the frame, a press head movable toward and from the buck in a downward and forward arcuate path with the upright portion of the path extending at nearly a right angle to the pressing face of the buck, and means for carrying and guiding the head in its movement; the combination of actuating mechanism comprising an upright lever pivotally connected at its upper end to the head carrying means, a fulcrum for the lever at a point spaced from the pivot of the lever and arranged to permit the lever to swing fore and aft about the fulcrum, whereby the lever moves forwardly and rearwardly about its fulcrum, a prime mover connected to the lever at a point spaced from the fulcrum and the pivoted end of the lever, fulcrum guide means coacting with the fulcrum to successively cause the lever to move on its fulcrum during the closing of the press from open to nearly closed position and to translate the rearward swinging movement of the lever into a downward pull link movement during the final closing movement, said means

including toggle links pivoted to each other and respectively to the frame and the fulcrum, and mechanism operated by the swinging movement of the lever by the prime mover and coacting with the toggle links to hold the toggle links folded during the initial closing movement of the press and to cause the toggle links to straighten and thereby cause the lever to act as a pull link when the press head reaches the upright portion of its arc of movement.

12. In a garment and laundry press comprising a frame, a stationary buck mounted on the frame, a press head movable toward and from the buck in a downward and forward arcuate path with the upright portion of the path extending at nearly a right angle to the pressing face of the buck, and means for carrying and guiding the head in its movement; the combination of actuating mechanism comprising an upright lever pivotally connected at its upper end

to the head carrying means, a fulcrum for the lever near its lower end arranged to permit the lever to swing fore and aft about the fulcrum, a prime mover connected to the lower portion of 5 the lever, fulcrum guide means coacting with the fulcrum to successively cause the lever to move on its fulcrum during the closing of the press from open to nearly closed position and to translate the rearward swinging movement of 10 the lever into a downward pull link movement during the final closing of the press, said means comprising a cam way having an upright dwell portion and an angular inclined portion leading from the lower end of the dwell portion, the 15 fulcrum having a follower coacting with the cam way and movable through the dwell portion during the movement of the lever about the fulcrum and into the angular inclined cam portion during the pull link operation of the lever.

ERNEST DAVIS.
